United States Patent Office.

HEZEKIAH MUNROE, OF FALL RIVER, MASSACHUSETTS.

Letters Patent No. 75,564, dated March 17, 1868.

IMPROVED CASTER FOR FURNITURE.

The Schedule referred to in these Letters Patent and making part of the same.

TO ALL WHOM IT MAY CONCERN:

Be it known that I, HEZEKIAH MUNROE, of Fall River, in the county of Bristol, and State of Massachusetts, have invented a new and improved Caster; and I do hereby declare that the following is a full, clear, and exact description thereof, which will enable others skilled in the art to make and use the same, reference being had to the accompanying drawings, forming part of this specification.

Figure 1 is a vertical central section of my improved caster through the line *x x*, fig. 2.

Figure 2 is a horizontal section of the same through the line *y y*, fig. 1.

Similar letters of reference indicate corresponding parts.

This invention refers to the improvement of casters for tables, bedsteads, stools, and other articles of furniture by the introduction of horizontal friction-rollers arranged around the spindle of the caster-wheels, whereby the latter will turn more freely and easily to the line of direction in which the article of furniture supported by it is moved, together with other parts perfecting the whole, as will hereinafter be more fully set forth.

In the drawings, A is the caster-wheel working in a yoke in the usual manner, and B is the tapering spindle of the same, which is contained for the most part in a hollow extension, D, arising centrally from the top of the case E, which contain the friction-rollers *e*, the spindles of which latter are the cylindrical parts of the screws *a*. These screws pass through the bottom disk *b*, the said disk serving to completely close the case E containing the friction-rollers. A central hole in the disk serves as a lower bearing for the spindle B, as shown. A flange or collar, *d*, turned or otherwise formed on the spindle, is so located that it will be above the friction-rollers, and thereby serve as a stop to prevent the caster-wheel from falling out when the article of furniture it supports is lifted from the floor, but otherwise serves as a flange to keep the spindle B centrally in the extension D, as shown in fig. 1. The friction-rollers, when properly fitted, will be in contact with the spindle, and effectively serve the end for which they are desired.

In practice the case and wheels are of cast metal. It is simple, cheap, and durable, and perfectly serves the purpose set forth.

I claim as new, and desire to secure by Letters Patent—

The construction and arrangement in the case E of the friction-rollers *e* upon the vertical screws *a*, and adapted to bear and revolve against the shank of the spindle B, below the collar *d* and above the bottom plate *b*, without contact with the top or bottom of the case E, as herein described for the purpose specified.

HEZEKIAH MUNROE.
